FUSE

John H. Woodberry, Johnsonville, S. C., Christian G. Storm, Washington, D. C., and John S. Barker, Rochester, N. Y., and Francis H. Miles, Jr., Mahwah, Harold M. Brayton, Dover, and Clifton E. Seavey, Rockaway, N. J., assignors to the Secretary of War of the United States of America, trustee

Application April 2, 1925, Serial No. 20,154

9 Claims. (Cl. 102—79)

(Granted under the act of March 3, 1883, as amended April 30, 1928; 370 O. G. 757)

1

The invention described herein may be manufactured and used by or for the Government for governmental purposes without the payment to us of any royalty thereon.

The subject of this invention is a fuse.

This invention relates primarily to a base detonating fuse designed particularly for armor piercing projectiles though not limited to this use. When a projectile enters armor at critical angles its tendency to straighten out produces a severe whipping action with the result that the fuse body is frequently distorted and the fuse mechanism deranged to render it inoperative.

The primary objects of this invention are to construct a fuse which will not be rendered inoperative under the conditions outlined in the preceding paragraph; to provide a delay train whose various elements combine in harmonious relation to insure proper and positive functioning without variation as to time in communicating the flame from a primer element to a detonating element; to position the delay train a relatively great distance from the primer; and, to interpose means for concentrating the flame from the primer.

Other and equally important objects and advantages are: to provide a casing for carrying an igniting mechanism and for compactly and effectively disposing a delay train of small diameter and high density between the igniting mechanism and the detonator; to absolutely obturate all of the gases generated by the burning powder, thus causing the powder to burn under a rising pressure; to provide an expansion chamber for the gases generated by the burning powder of the delay train to the end that sufficient expansion volume may be obtained to permit the pressure developed from the burning powder to be controlled so that the entire element may be made gas tight; to interpose the delay train between the plunger, in which is carried the firing pin, and a rotor, in which is carried the detonator, each of which elements are provided with safety devices to normally hold them in unarmed position; and, to provide means for positively locking the rotor in unarmed position during flight and for insuring this position on impact, especially on ricochet action.

To these and other ends, our invention consists in the construction, arrangement, and combination of elements, described hereinafter and pointed out in the claims forming a part of this specification.

A practical embodiment of our invention is 55 consisting of an anvil 32 abutting an internal

2

illustrated in the accompanying drawings, in which,

Fig. 1 is a longitudinal sectional view of a fuse constructed in accordance with the invention;

Fig. 2 is a similar view taken at right angles to Fig. 1;

Fig. 3 is a sectional view taken on the line 3—3 of Fig. 2;

Fig. 4 is a detailed longitudinal sectional view 10 of the casing; and

Figs. 5 and 6 are detailed sectional views of the rotor.

Referring to the drawings by numeral characters of reference:

15 The fuse comprises a body 10, its rear portion formed with a plurality of bores to form a rear cavity 11, an intermediate cavity 12, and a front cavity 13, in which are respectively disposed a plunger casing A, a forwardly extending eccentric portion formed integrally with the plunger casing to constitute a delay train casing B, and a detonator carrier C. The cavities 12 and 13 are eccentric for purposes which will hereinafter appear.

25 The forward portion of the fuse body is formed with a booster chamber 14 closed by a threaded plug 15 and in communication with the front cavity 13 through a passage 16. The forward end of the passage 16 is provided with an annular shoulder 17 for seating a cup 18 to separate a booster charge 19 from the detonator carrier C.

The casing AB is retained in the body 10 by a rear plug 20 and is held against rotation by reason of its eccentric portion B.

35 The enlarged portion A of the casing is chambered to carry a plunger consisting of a cup 21 in which is held by a pin 22 a slotted carrier 23. Pivotally supported in the carrier as at 24 and normally housed in the slot is a firing pin 25

40 which is normally held in unarmed position by means of bolts 26 registering within an aperture of the firing pin through springs 27 and adapted to be thrown out by centrifugal force during the rotational flight of the projectile to release the

45 firing pin to armed position. The plunger is held in rearward position until impact of the projectile by means of a spring 28 embracing the forward part of the carrier and confined between the plunger cup and the dividing wall 29 of the casing AB.

The dividing wall is recessed to receive a primer retainer 30 crimped into place and formed with a central flared aperture 31. The wall is further recessed to carry an igniting mechanism

annular shoulder 33 and capped by a primer cover 34 which seats in the retainer 30. Disposed between the cover and the anvil is a primer composition 35 and a disc 36.

The anvil is formed with ducts 30' in communication with a passage 37 which extends through the length of the casing B axially of the fuse and terminates in a reduced mouth 38. The wall of the passage is crimped or upset as at 39 intermediate its length to firmly hold in its central portion a plug 40 which serves to retain a delay train, positioned forward thereof. The plug is formed with a converging aperture 41 for concentrating the flame from the primer and abuts a pellet 42, which is formed with a depression 43 which registers with the edges of the aperture 41 to form, as it were, an apical cap.

Adjacent the pellet 42 is a special delay element 44 which element abuts against a partially closed cup 45 resting against the shoulder formed by the reduced mouth 38 and containing an exciter charge 45'. The central train consisting of the pellet 42, element 44, and charge 45' is of small diameter and compressed to a high density to withstand very severe impact.

The casing B is further formed with an expansion chamber 46 in communication through a port 47 with a chamber 37' formed in the passage 37 by reason of the position of the plug 40. The expansion chamber is closed by a plug 48 which is crimped into place. The object of this chamber is to obtain sufficient expansion volume so that the gases from the burning powder may be obturated and develop a continually rising pressure. This insures greater uniformity in the delay period and assists the detonating wave from the exciter 45' to the detonating element 59 in the carrier C.

Rotatably mounted in the eccentric cavity 43 on a pin 49 is the detonator carrier C in the form of an approximately T-shaped rotor, which is normally held by pins 50 to position a blind cavity 51 formed in one wing of the rotor in alignment with the delay charge. The pins are carried in the fuse body, one of them being at an angle, and are projected in the cavity 43 by springs 52 acting against screw heads 53. During rotational flight of a projectile the pins are thrown out under the action of centrifugal force thereby permitting the rotor to rotate on its axis until it engages a stop pin 54, at which time, a locking pin 55 disposed horizontally in the rotor will be thrown outward by centrifugal force to partially enter an aligned opening 56 in the fuse body until it is brought up against a plug 57 when a pin 58 carried by the rotor vertical to the pin 55, may creep forward until it is behind the locking pin 55 to prevent its return at the moment of impact. If the vertical pin 58 is not already in locking position at the moment of impact it will be urged forwardly under the force of inertia.

When the rotor is in this position it will dispose a detonating element 59 axially of the fuse and in line with the relay charge on the one side and the booster charge on the other. The detonator is carried in a cup 60 which is frictionally held in an aperture 61 passing entirely through a wing of the rotor.

During transportation and storage the fused shell will be entirely safe as the firing pin and detonator at opposite ends of the igniting mechanism and delay train are respectively maintained in unarmed position by the plunger bolts 26 and the centrifugal pins 50 which are not 75

released until the projectile attains a predetermined rotational speed during flight.

As stated, the firing pin being released to armed position during flight, it is held from the primer by means of the plunger restraining spring until the impact of the projectile causes the plunger to move forwardly under the force of inertia until the firing pin primes the primer. The flame from the primer ignites the delay train and is transmitted by the relay charge to the detonator which explodes the booster charge.

The particular composition and arrangement of the delay train and its disposition with respect to the igniting mechanism and the detonator are designed to provide a simple, compact, and highly efficient device embodying the most desirable objects to be sought in fuse construction, while the method of housing these elements insures positive functioning under all conditions of impact.

While in the foregoing there has been illustrated and described such combination and arrangement of elements, as constitute the preferred embodiment of our invention, it is nevertheless desired to emphasize the fact that interpretation of the invention should only be conclusive when made in the light of the subjoined claims.

We claim:

1. A fuse including a fuse body, a casing within the body, said casing formed with an eccentric portion, an igniting mechanism carried by the casing, a delay train disposed in the eccentric portion, a rotor mounted in the body forwardly of the casing, a detonator carried by the rotor, means for locking the rotor in armed position during flight, means for insuring the arming position of the rotor on impact, and a booster charge carried by the fuse body forwardly of the rotor.

2. A fuse including a fuse body, a casing within the body, said casing formed with an eccentric portion, an igniting mechanism carried by the casing, a delay train disposed in the eccentric portion, said portion formed with a chamber in communication with the delay train.

3. A fuse including a rotor, a firing element carried by the rotor, means for holding the rotor in unarmed position, means for limiting the rotational movement of the rotor, a pin disposed horizontally in the rotor and adapted to be thrown outward by centrifugal force to engage the fuse, and a pin disposed vertically to the aforesaid pin and adapted to seat behind said pin to positively lock the rotor in armed position.

4. A delay train for fuses including a pellet, said pellet formed with a depression in its rear face, a special delay powder loaded forwardly of the pellet and an exciter charge adjacent the special delay powder, said train being of small diameter and high density.

5. A fuse embodying an igniting mechanism, a delay train composed of several elements, a plug disposed between the igniting mechanism and the delay train, said plug formed with a forwardly converging aperture and the element of the delay train adjacent the plug formed with a central depression.

6. A fuse embodying an igniting mechanism, a delay train, a plug spaced from the igniting mechanism and abutting the delay train, said plug formed with a converging aperture.

7. A fuse embodying an igniting mechanism, a detonator, a delay train disposed between the

igniting mechanism and the detonator, and means spaced from the igniting mechanism and abutting the delay train for concentrating the flame from the igniting mechanism.

8. A delay train for fuses including an exciter charge, a special delay powder adjacent the exciter charge, a pellet adjacent the delay powder, said pellet being formed with a depression in its face opposite the delay powder, and means for concentrating an igniting flame upon said depression.

9. A compressed delay train for fuses including

means for concentrating an igniting flame, a pellet having a depression in position to receive the concentrated flame, a special delay powder abutting the pellet, and an exciter charge abutting the special delay powder.
